UNITED STATES PATENT OFFICE.

CORNELIUS B. HARDMAN, OF COLUMBUS, OHIO.

BALING-PRESS.

1,261,931.

Specification of Letters Patent. Patented Apr. 9, 1918.

Application filed August 16, 1917. Serial No. 186,457.

To all whom it may concern:

Be it known that I, CORNELIUS B. HARDMAN, a citizen of the United States, residing at Columbus, in the county of Franklin 5 and State of Ohio, have invented certain new and useful Improvements in Baling-Presses, of which the following is a specification.

This invention relates to baling presses 10 and has particular reference to the mechanism for inserting the division boards to give proper length to the bales and to facilitate the proper wiring thereof.

The main object of my invention, therefore, resides in a structure of block dropper which is yieldingly supported in position 15 so that in case of improper manipulation, the block dropper will yield rearwardly to avoid all breakage. In this connection, my 20 block dropper is preferably movable from a lowered position to an elevated position or from an operative to an inoperative, with the supporting structure so arranged and mounted to permit its rearward yielding 25 movement under abnormal conditions.

Another object of my invention also resides in the combination with a block dropper movable from a lower to an upper position, of a peculiar type of placer clip designed to normally engage the top edge of a block, but which is so formed along its outer face portion to prevent it from engaging 30 the transverse slots in the block itself should this latter not be in proper position 35 at the time the feeder head descends.

The preferred embodiment of my invention is shown in the accompanying sheet of drawings, in which similar characters of reference designate corresponding parts, 40 and in which:

Figure 1 is a view in perspective of a baling press with the parts broken away showing my improved type of block dropper,

Fig. 2 is a view in perspective of my improved block dropper shown detached and shown in lowered position, and,

Fig. 3 is a fragmentary perspective of a portion of the feeder head and block dropper,

In Fig. 1, the body of the baling press is designated generally by the reference numeral 1. A plunger or head block 2 is designed to reciprocate back and forth with- 55 in the bale chamber 3 in the customary manner and the feeder head 4 is designed to move up and down by means of its actu-

ating mechanism designated generally by the reference numeral 5. On the top of the rear portion of the press, I mount a plate 6 which forms the support for the block dropper itself. This block dropper comprises a rectangularly shaped holder member 7 provided with a pair of spring clips 8 at its lower forward portion to frictionally hold 65 the block 9 in position until the latter is engaged by the placer clip 10 carried by the feeder head 4. The holder member 7 is provided with a pair of downwardly extending legs 11 which are pivotally mounted to the 70 cross rod shown at 12. This latter is slidably mounted within the slots 13 of the supporting clips shown at 14 which supporting clips extend rearwardly and are then bent at right angles, as shown at 15. The ends 75 of the pivot rod 12 project through the slots 13 and these slots are of sufficient length to permit the proper rearward movement of the block dropper under abnormal conditions, as will be presently related. A pair 80 of bolts 16 extend longitudinally of each of the frame pieces 14 and are provided with a clevis head 17 at their forward ends. These clevis heads are made to embrace the legs 11 and also engage the cross rod 12 as shown. 85 The bolts themselves project rearwardly through the inturned ends 15 of the frame pieces 14 and springs 18 encircle these bolts between their two points of support.

A big difficulty in the use of these baling 90 presses has been found to be the scarcity of skilled help to properly manipulate the block dropper. A frequent faulty operation is one wherein the block dropper is not moved to its extreme upright position as 95 the feeder head descends, with the result that the placer clip 10 engages the front face of the block to cause a jam, with the result that either the feeder head or the block dropper has to break. In my construction, should the block dropper not be properly elevated, the springs 18 will yield sufficiently to permit the rearward movement of the block dropper as a whole and thus guard against unnecessary and undue 100 breakage. The springs 8 hold the block 9 in position with sufficient firmness to prevent its dislodgment through the body 7 under these conditions and the result is that the entire block support structure moves 110 rearwardly against the tension of the springs 18.

To prevent the placer clip 10 from obtaining a firm grip in one of the transverse

slots 19 formed in the blocks 9, I have provided a clip wherein the bottom portion 20 is substantially flat to engage the top edge 21 of the blocks and an upstanding face 22 also substantially flat with a rounded corner 23 between these two portions. This flat face 22 is preferably inclined to bring the corner 23 away from the block 9 when the feeder head is near the end of its stroke as 10 may be deduced from the showing in Fig. 1, to absolutely prevent it catching in any of the slots 19 should the block not have been properly elevated. It will be understood that it is necessary to provide the 15 blocks 9 with the slots 19 in order to facilitate the manipulation of the binding wires. In case the block is in only a partially elevated position, the rounded corner 23 cannot engage any of the small slots 19 because 20 of its curvature and thus there is presented a rolling action out of the slots as the feeder head descends, and the flat front face 22 finally lies parallel with the front face of the block and then in an inclined relation 25 therewith and in this manner the entire block supporting structure is pushed rearwardly against the tension of the springs 18.

What I claim, is:

1. In a baling press, the combination with 30 a feeder head, of a block dropper comprising a holder member pivotally supported on the press to swing between a lower and an upper position into or out of the path of movement of said feeder head, and means for 35 permitting said pivotal connection a yielding movement away from said feeder head under abnormal conditions.

2. In a baling press, the combination with 40 a feeder head, of a block dropper comprising a holder member, means for pivotally supporting said holder upon the press to swing between a lower and an upper position into or out of the path of movement of said feeder head, and means for yieldingly 45 holding said pivot support in normal position but permitting its rearward movement under abnormal conditions.

3. In a baling press, the combination with 50 a feeder head, of a block dropper comprising a holder member, a transverse rod upon which said holder is pivotally mounted, means for supporting said rod to permit it an appreciable rearward movement, and spring means normally holding said rod in 55 its forward position.

4. In a baling press, the combination with 60 a feeder head, of a block dropper comprising a holder member, a pair of downwardly projecting legs on said member, a pair of slotted clips carried by the press, a rod supported in said slots to which said legs are pivoted, a pair of rearwardly extending bolts secured to said rod at their front ends

and suitably supported at their rear ends, and a spring carried by each rod between 65 its points of support.

5. In a baling press, the combination with a feeder head, of a block dropper comprising a holder member supported on said press to swing from a lower to an upper 70 position and supported to yield rearwardly under abnormal conditions, and a placer clip on said feeder head provided with a block engaging surface sufficiently rounded to slide over the face of the block under ab- 75 normal conditions.

6. In a baling press, the combination with a feeder head, of a block dropper comprising a holder member supported on said press to swing from a lower to an upper position 80 and supported to yield rearwardly under abnormal conditions, and a placer clip on said feeder head formed with a substantially flat bottom for engaging the end of the block and a substantially flat front side at sub- 85 stantially right angles to the bottom but formed with a rounded corner portion between said bottom and side.

7. In a baling press, the combination with a feeder-head, of a block dropper comprising a holder member mounted to move between an operative and an inoperative position into or out of the path of movement of said feeder head, and means for permitting said member a yielding movement away 95 from said feeder head under abnormal conditions.

8. In a baling press the combination with a feeder head of a block dropper comprising a holder member mounted to move between an operative and an inoperative position into or out of the path of movement of said feeder head, means for permitting said member a yielding movement away 100 from said feeder head under abnormal conditions, and a placer clip on said feeder head adapted to disengage itself from the grooves in the block during the descent of said feeder head under abnormal conditions.

9. In a baling press, the combination with 110 a feeder head member of a block dropper member mounted on the press to move between an operative and an inoperative position into or out of the path of movement of said feeder head, and means for permitting 115 one of said members a yielding movement away from the other a sufficient distance to permit them to pass each other under abnormal conditions and on the descent of said feeder head member.

In testimony whereof I affix my signature in presence of two witnesses.

C. B. HARDMAN.
